HARVEY KONHEIM, OF NEW YORK, N. Y.

METHOD OF REPRODUCING ELECTRICAL OSCILLATIONS AND APPARATUS THEREFOR.

Application filed October 29, 1926. Serial No. 144,990.

My invention relates to the art of electrical reproducers and deals more specifically with a loud speaker system.

It is an object of my invention to provide a 5 loud speaker device which will respond equally throughout the range of audible frequencies.

It is a further object of my invention to provide a loud speaker device which is supplied 10 with oscillations of a band of frequencies which does not include the natural period of the loud speaker device.

Further it is an object of my invention to provide a plurality of loud speaking units 15 each of which is responsive primarily to a separate portion of the audible spectrum of frequencies.

Further it is an object of my invention to provide a plurality of selective amplifiers 20 each of which is designed to emphasize certain separate portions of the audible spectrum.

And it is a further object of my invention to provide a loud speaker device with a filter 25 to limit the range of frequencies supplied to the loud speaker device.

These and other objects of my invention will be apparent readily to one skilled in the art from the following description taken in 30 connection with the accompanying drawing in which:

Figure 1 shows a characteristic of an ideal loud speaker device.

Figures 2 and 3 show characteristics of the 35 usual type of loud speaker devices, having a natural resonant frequency at the lower and the upper portion of the audible spectrum, respectively.

Figures 4 and 5 show certain characteristics of the amplifiers embodied in my invention.

Figures 6 and 7 show the characteristics of the loud speaker devices when operated by the amplifiers embodied in my invention.

Figure 8 shows the resultant characteristic of my loud speaker device.

Figure 9 is a diagrammatic view showing a complete radio receiving system embodying my invention.

In order to obtain good reproduction of the speech and music frequencies, it is necessary to provide a loud speaker device which has among other properties a straight line characteristic such as shown in Figure 1.

That is, it is necessary to obtain an even response of the vibrating element for all of the

frequencies within the audible spectrum which extends approximately from 50 cycles per second to 5000 cycles per second. It is well known, however, that practically all 60 loud speakers of the horn or cone types have a resonant frequency of their own at some frequency within the audible spectrum and when the frequencies to be reproduced approach the natural period of the loud speaker 65 there is an unnatural and artificial over-emphasis of these frequencies, which results in a bellowing and distortion of the sound emitted. Many attempts have been made to construct an aperiodic loud speaker which 70 would eliminate this resonant effect but these attempts have not been wholly successful.

I overcome this undesirable effect by providing a plurality of loud speaker units each of which has a natural period of vibration at 75 points widely removed from each other in the audible spectrum, such as shown, for example, in Figures 2 and 3 of the drawing. Each of these loud speaker units is then supplied with electrical oscillations from a separate 80 amplifying unit, which is of the selective type and which is designed to emphasize one portion of the audible spectrum, while it suppresses frequencies in the remaining portion of the spectrum. These amplifiers have the 85 characteristics such as shown in Figures 4 and 5 of the drawing. Thus an amplifier having the characteristic shown in Figure 4 will suppress the lower portion and emphasize the upper portion of the audible spectrum; while an amplifier having the characteristic shown in Figure 5 will emphasize the lower portion and suppress the upper portion 90 of the audible spectrum.

As a result of this combination of amplifiers and loud speaker units each loud speaker device is designed to reproduce all the frequencies over a portion only of the spectrum in which its response is a straight line function of the frequency. For the frequencies 100 which include the natural period of the loud speaker, however, the response is made slight due to the selective feature of the amplifier. A loud speaker device having a characteristic of the type shown in Figure 3 when operated by an amplifier having a characteristic of the type shown in Figure 5 will give a characteristic such as shown in Figure 7. Similarly a characteristic such as shown in Figure 6 will be obtained by the operation of 105 a loud speaker device having the characteristic shown in Figure 2 by means of an ampli-

fier having the characteristic shown in Figure 4.

The output of the various loud speaker devices may be readily combined in any manner well known in the art such as by feeding the same into a common horn. The composite sound rendered by these various loud speaker devices will have a characteristic such as shown in Figure 8.

10 Referring now to Figure 9 I will describe a complete system embodying my invention:

15 Incoming radio signals may be intercepted at 11 and impressed upon the tuned circuit 12 of the vacuum tube 13 which acts as a radio frequency amplifier. Coupled to the tube 13 at 14 is a detector 15, the output of which is coupled to the amplifier 17 by means of the transformer 16. The details of this receiving equipment is not at all important for the 20 purposes of the present invention and any other well known radio receiving system may be substituted therefor. Alternatively locally produced oscillations such as those of an electro-magnetic pick-up or other electric 25 phonograph devices may be substituted for the radio receiver. The selective amplifiers indicated generally by A and B are coupled to the output circuit of the amplifier 17 by means of the transformers 18 and 19 respectively. Rheostats 20 and 21 are provided as a convenient means of apportioning the amount of energy which will be supplied to primaries of the respective transformers 18 and 19.

30 35 I will now describe in detail the selective amplifiers which are designed to amplify one portion of the audible spectrum and to suppress the remaining portions of the audible spectrum.

40 45 Selective amplification as I have disclosed it involves the combination of certain predetermined external impedances with the internal impedances of the vacuum tubes used. In an impedance coupled amplifier system, as disclosed in my application, there are three external impedances characteristic of each stage. For example, considering tube 29 of Fig. 9 the external impedances are:

1. Coupling impedance 27.
- 50 2. Input impedance 28.
3. Output impedance 30.

The three internal impedances of tube 29, for example are:

- 55 1. The impedance between grid and filament, commonly referred to in the art as R_g , is the internal impedance of the tube.
2. The impedance between the filament and plate is the internal output resistance, commonly referred to as R_p .
- 60 3. The capacity between grid and plate, commonly referred to as the inherent capacity of the tube.

I utilize a combination of the six impedances listed above to obtain selective amplification. Thus, for each stage, the amplifica-

tion will be a maximum when the coupling impedance is small, the output impedance large relative to the internal input resistance, and the output resistance large relative to the internal output resistance of the tube.

70 Referring first to the amplifier A, the secondary of the transformer 18 is included in the input circuit of the vacuum tube 25. In the output circuit of the vacuum tube 25 I provide the choke coil 26 which is of a low 75 impedance. The coupling condenser 27 is of relatively small capacity. The vacuum tube 29 is coupled to 25 through the condenser 27, and the input circuit of the tube 29 is provided with the grid-return 28. In the output 80 circuit of the tube 29 I also provide a choke 30 and condenser 31 both of which have the same properties as the elements 26 and 27 respectively. In the output circuit of the tube 29 I also connect the filter 32 which may consist of any suitable net-work of inductances and capacitances for the purpose of checking any undesirable electrical oscillations in the reproducing unit 33. The output of the reproducer 33 is conducted to the horn 35 90 through the passage 34.

This amplifier has its selective characteristic for the following reasons:

95 When the electrical oscillations of varying frequencies are impressed upon the transformer 18 amplification will start only when frequencies high enough to find the impedance of the choke coils 26 and 30 approximately as great or greater than the plate impedances of the amplifying tubes, and also 100 when the conductivity of the condensers is about as great or greater than that of the grid-return 28. Thus the system A will amplify only those frequencies which are 105 above a predetermined value.

In order to amplify the lower portion of the audible spectrum I provide the amplifier B which has the vacuum tube 45 coupled to the common source of electrical oscillations of the amplifier 17, by means of the 110 transformer 19. In the output circuit of the vacuum tube 45, I provide the choke coil 46 and the parallel condenser 47. The vacuum tube 51 is connected to the tube 45 through the large condenser 48, and choke coil 49. 115 Tube 51 is provided with the grid-return 50. In the output circuit of the tube 51 I provide the choke 52, condenser 53 and large condenser 54 all of which have the same properties as the previously described elements 120 46, 47 and 48, respectively. In the output circuit of the tube 51 I also connect the filter 55 which like filter 32 is designed to suppress undesirable frequencies, and to the filter 55 I connect the reproducing unit 56, which 125 feeds its output into the loud speaker 35 through the passage 57.

The amplifier B has its feature of selectivity for the following reasons:

The choke coils 46 and 52 are big enough 130

to block all audio frequencies effectively. The coupling condensers 48 and 54 are of high capacity and are designed to practically short circuit all audio frequencies. The chokes 46 and 52 are bypassed by small condensers 47 and 53 which provide a path for the oscillations of the higher frequencies. In the grid circuit of the tube 51 the small choke 49 blocks the higher frequencies. This system will amplify, therefore, only signals of a frequency low enough to find an impedance about as great or greater than the plate impedance of the tubes 45 and 51 in the condensers 47 and 53, respectively, and which will find through the choke 49 a conductivity about as great or greater than that of the grid-return 50.

While I have disclosed a specific amplifier structure it is to be understood that such amplifier is merely shown for the purposes of illustration of the invention, and that many modifications of the same may be made by any one skilled in the art without departing from the spirit and scope of this invention as defined by the appended claims.

Having thus described my invention I claim:

1. An amplifier for electrical impulses comprising in combination, a first unit constructed and arranged to amplify comparatively slightly electrical impulses having a predetermined band of frequencies and to amplify comparatively greatly another band of said frequencies, a second unit constructed and arranged to amplify greatly said impulses which said first mentioned unit amplifies slightly and to amplify slightly said impulses which said first mentioned unit amplifies greatly, and separate acoustic devices associated with each of said units.

2. An amplifier comprising in combination, a plurality of selective amplifying units, each of said units being designed to emphasize a predetermined range of frequencies and to suppress all other frequencies, and a separate acoustic device associated with each of said units, each of said devices having a natural period of vibration which is outside of the range of frequencies which its associated unit is designed to emphasize.

3. In a radio receiving system means to convert electrical oscillations of varying frequencies into sound impulses which comprises, a first unit adapted to amplify oscillations of certain frequencies and to suppress oscillations of other frequencies, a second unit adapted to amplify oscillations of a frequency which said first unit is adapted to suppress and to suppress oscillations of a frequency which said first unit is adapted to amplify, and separate acoustic devices associated with each of said units.

4. In a radio receiving system adapted to reproduce electrical impulses having a range

of frequencies varying from the lower limit of audibility to the higher limit of audibility, the combination of an amplifier comprising a plurality of selective amplifying units, each of said units being designed to amplify a separate predetermined band of said frequency range to a higher degree than any other of said frequencies, and separate acoustic devices associated with each of said units to convert the electrical impulses amplified thereby into sound vibrations.

5. In a radio receiving system adapted to reproduce electrical impulses having a range of frequencies varying from the lower limit of audibility to the higher limit of audibility, the combination of an amplifier comprising a plurality of selective amplifying units, each of said units being designed to amplify a separate predetermined band of said frequency range to a higher degree than any other of said frequencies, separate acoustic devices associated with each of said units to convert the electrical impulses amplified thereby into sound vibrations, and means interposed between each unit and its associated acoustic device to permit the passage therebetween of impulses of predetermined frequencies only.

6. In a system for reproducing electrical oscillations, a vacuum tube amplifier having an output circuit, a first selective amplification unit coupled to said output circuit and arranged to amplify comparatively slightly electrical impulses having a predetermined band of frequencies and to amplify comparatively greatly another band of said frequencies, a second selective amplification unit coupled to said output circuit and arranged to amplify greatly said impulses which said first mentioned unit amplifies slightly and to amplify slightly said impulses which said first mentioned unit amplifies greatly, and separate adjustable means to vary the amount of energy transferred to each of said first and second selective amplification units from said output circuit.

7. In a system for reproducing electrical oscillations, a vacuum tube amplifier having an output circuit, a first coupling device, a second coupling device, both said devices being connected in parallel in said output circuit, a first unit coupled to one of said devices adapted to amplify oscillations of certain frequencies and to suppress oscillations of other frequencies, a second unit coupled to said other device adapted to amplify oscillations of a frequency which said first unit is adapted to suppress and to suppress oscillations of a frequency which said first unit is adapted to amplify, and separate means connected in series with each of said devices selectively to vary the amount of energy transferred by said coupling devices to said units.

HARVEY KONHEIM.
